UNITED STATES PATENT OFFICE

EDWIN W. NORTH, OF ROCKFORD, ILLINOIS, ASSIGNOR TO NATIONAL LOCK CO., OF
ROCKFORD, ILLINOIS, A CORPORATION OF DELAWARE

HINGE

Application filed June 15, 1931. Serial No. 544,334.

This invention pertains to hinges and more particularly to a concealed pintle hinge especially suited for light service such as cabinet use although it will be manifest that the principles involved may be utilized to advantage upon heavy hinges.

It is the purpose of this invention to provide a hinge embodying a concealed pintle enclosed in such a manner that the hinge may be constructed economically both from the point of view of the amount and kind of material used and the steps involved in the fabrication of the material into a hinge.

Heretofore concealing the pintle of a hinge has involved relatively expensive construction, that is, the manufacture thereof was costly not only from the point of material being used but from the shaping and forming of the material into a concealed pintle hinge.

20 In accordance with this invention it is not only possible but practical to manufacture, commercially in large quantities, concealed pintle hinges by stamping or pressing the wings of the hinge from sheet metal. In the

25 preferred form the base or stationary wing is provided with a pair of opposed hollow pintle supporting pockets and is also provided with integral locking members which retain the pintle within the supporting pocket.

30 A better understanding of this invention will be had from the following description given in connection with the drawing, in which:

Fig. 1 is a section taken in a horizontal plane along line 1—1 of Fig. 2.

Fig. 2 is a front elevation of a hinge embodying the features of this invention.

Fig. 3 is a rear elevation of the same.

Fig. 4 is a section on line 4—4 of Fig. 2.

40 Fig. 5 is a partial section taken on line 5—5 of Fig. 2.

As can be seen from the drawing in the illustrated embodiment of this invention, a hinge is shown that is particularly suitable for cabinet doors and comprises a relatively stationary or base wing 1 to which is pivotally connected a moving wing 2 by means of a pintle 3.

The stationary wing is a relatively long 50 narrow plate of sheet metal having a pair of

opposed spaced pintle pockets 4 struck outwardly from one face thereof. These pockets being struck out from the sheet metal wing are hollow and provide spaced recesses 6 upon their under side and closed at one end for receiving and concealing the ends of the pintle. The pintle may be knurled at one or both ends if desired. The base wing is also provided at one edge adjacent the two pintle pockets with a pair of tongues 7 one adjacent each pocket which may be curled around the ends of the pintle to retain the same within the recesses.

The moving wing 2 is provided at one edge with a tongue 8 of reduced width equal to the distance between the pintle pockets which may be curled about the intermediate portion of the pintle. The shoulders 9 formed by forming the reduced tongue 8 strike the edge 10 and limit the movement of the wings in one direction.

From the foregoing description it will be observed that a concealed pintle hinge has been provided which may be readily manufactured from sheet stock, and in which the pintle is entirely enclosed and secured in position by a pair of tongues formed integrally with the base wing by curling them about the pintle after the wings have been assembled, to effectively lock the wings pivotally together. The hinge may be cheaply manufactured since it involves only stamping of sheet stock. The construction provides a very neat and very rugged hinge due to the pintle being securely supported at both ends and the entire intermediate portion of the movable wing providing a long bearing for the latter wing.

It will be obvious that minor changes may be made in the details of construction and that the hinge may be constructed of material other than sheet stock without departing from the spirit and scope of the invention as defined in the appended claims.

I claim:

1. A hinge comprising a pair of wings and a pintle pivotally securing said wings together, one of said wings having a pair of spaced pockets arranged to receive the ends of said pintle and a pair of integral tongues projecting from said wing and curled in-

wardly around the ends of said pintle to secure the same within the pockets.

2. In a hinge: a hinge member having a pintle whose end portions extend outwardly from its opposite sides; a second hinge member made of sheet metal having spaced hollow extensions embracing the first-mentioned hinge member and covering the pintle's end portions, said extensions having tongues bent under said end portions respectively to connect the hinge members together turnably.

3. In a hinge: a hinge member having a pintle whose end portions extend outwardly from its opposite sides; a second hinge member made of sheet metal having spaced hollow conical extensions embracing the first-mentioned hinge member and covering the

pintle's end portions, said extensions having tongues bent under said end portions respectively to connect the hinge members together turnably.

4. A hinge comprising a pair of wings, a pintle pivotally securing said wings together, one of said wings having a pair of spaced pockets arranged to receive the ends of said pintle, said latter wing also having an integral tongue projecting therefrom and extending over one end of said pintle to secure the latter in one of said pockets and means for securing the other end of said pintle in its associated pocket.

In witness of the foregoing I affix my signature.

EDWIN W. NORTH.
